C. J. PAULSON

VENDING MACHINE

Original Filed April 22, 1921

Inventor

Charles J. Paulson
By his Attorney
J. Parker

UNITED STATES PATENT OFFICE.

CHARLES J. PAULSON, OF BROOKLYN, NEW YORK.

VENDING MACHINE.

Application filed April 22, 1921, Serial No. 463,651. Renewed July 1, 1926.

This invention relates to vending machines and my present improvements are directed particularly to automatic means for detecting and rejecting light weight coins, disks, slugs, washers and other devices with which it is not uncommon to attempt to operate coin-controlled mechanism. With the vending machines at present in use these fraudulent practices have met with some success 10 because the preventive means hitherto known and employed have not been wholly efficient, and this lack of positively preventive means against the operative employment of other than the actual coins for which a given 15 vending device is intended has led to the production of the present invention.

My invention also includes means for preventing the choking of a vending machine with coins or disks.

Essentially my improvements may be said to comprise:—

(1) The employment of gravity intercepting means in the coin chute which prevents the passage of a light weight disk and instead ejects it from the side of the chute.

(2) Means including the arrangement of a coin chute relatively to the point of operative lodgment for a coin whereby following coins or disks entering the chute, to choke it, will be deflected by the lodged coin and ejected from the side of the chute.

(3) The employment of means whereby coins, disks or slugs that are of smaller size than the particular coin for which the machine is designed, will, if of sufficient weight, pass through the chute, but will fail to become lodged in the mechanism thereof, to perform the useful function which it is the part of a designated coin to perform.

(4) Means whereby spurious coins or disks composed of magnetizable material will be deflected and ejected from the side of the chute by a magnet that is so located with respect to the lateral ejection outlet of an inclined chute as to be highly effective in ejecting disks of this character.

(5) Means for impaling washers or disks having a central orifice if these should become lodged in the operative part of the machine, the impaling means serving to cause the ejection of this class of fraudulent device in the attempted operation of the machine thereby.

(6) Means whereby the entrance to the coin chute is so angled with relation to the receiving slot (which latter is just of suf-

ficient dimensions to receive a designated coin) that a rectangular blank, not too wide to enter the slot, though capable of operative lodgment in the machine, is prevented 60 from passing into the chute.

Other features and advantages of my invention will hereinafter appear.

In the drawing:—

Figure 1 is a vertical, side sectional view 65 of a portion of a vending machine including my improvements.

Fig. 2 is an enlarged, front elevation thereof, and

Fig. 3 is an enlarged detail view of the 70 mechanism for the rejection of orificed coins or disks.

While the invention comprised in the present application is capable of employment with vending machines in general, I have 75 applied its features to the machine which is the subject of my earlier patent application Serial No. 451,948 filed March 14, 1921, and I therefore illustrate herein a portion of the mechanism of said earlier application 80 as an example of the operative character of these present improvements.

My said earlier application included a plunger 1, operating in a guide 2, and having a handle 3 by which it could be pulled 85 forwardly against the retractile energy of a spring 4. A regulator plate 5, pivoted to the lower end of a lever 6, and provided with a coin lodgment seat 7, has that seat located normally beneath a coin slot 8 in the plunger, so that a coin A delivered to slot 8, lodges in seat 7 and thereby unites the plunger 1 and plate, and when the plunger is pulled forwardly it draws the plate 5 with it, thereby operating the lever 6 against the 90 retractile energy of a spring 9, that performs certain article ejecting and other functions, not necessary to repeat herein.

The guide 2 has a forward cam device 10 and the plate 5 has a portion 11 that engages said cam device, when said plate is pulled forwardly, to release the seat 7 from the coin, the plate 5 in that release action working against a return spring 12, and the spring 12 causing the return to normal position of plate 5 before the plunger has reached the limit of its outward stroke, whereafter the coin is free to drop into a coin receptacle.

The particular features of the foregoing 110 assemblage to be noted in conjunction with my present improvements are the coin slot

8 in plunger 1, and the coin seat 7 in plate 5. Said slot 8, in the normal position of plunger 1, is located beneath a chute 13, which is to conduct a coin to slot 8 for lodgment in the coin seating slot 7 of plate 5.

The chute 13 is a straight, flat tube, open at both ends but arranged at a slight edge-wise inclination, its lower end, for coin delivery, being set somewhat off centre with respect to the slot 8, into which it is to deposit a coin for operative purposes. Thus, the forward edge (in Fig. 2) of chute 13, which at its lower portion has a coin ejection opening 14, extends beyond the confines of slot 8, but the rearward edge thereof, at the same lower portion, is given an inward curved surface 15, which continues into an outward curvature 16, that terminates, at the chute end, just within the vertical plane bounding the rear edge of slot 8, above said slot.

The purpose of the curvature 15—16 is to cause a designated coin, falling angularly through the chute, to be guided in its emergence from the chute so that it will fall into slot 8, and, while lodged in seat 7 will project above slot 8 in manner to present its upper segment tangentially to the base of a following coin or disk which latter will thereby become deflected upon striking said seated coin and be ejected through opening 14, in this way positively preventing the chute from becoming choked, either with designated coins, or with disks or slugs.

The chute 13, at its upper, forward portion has an edge opening 17, with an outwardly angled lip 18 that lies beneath a coin slot 19 in a cover plate 20. The slot 19 is gauged to just clearly receive a designated coin, and is located in its superposed relation to the chute 13 to deposit a coin upon the lip 18, so that the coin will enter the chute angularly, but the space between the plate 20 and the top edge of lip 18 is insufficient to permit the entry into the chute of a rectangular blank whose width is about equal to the diameter of the designated coin.

Pivoted at 21 to lugs 22 upon the chute, at an intermediate point thereof, is a pawl or interceptor 23 having an end, inclined seat or ledge portion 24 that lies within the chute, in the path of a falling coin or disk, said pawl being balanced by a weighted portion 25 that normally holds said pawl in its intercepting position in the chute to prevent the passage therethrough of an object whose weight is less than that of a designated coin. Therefore a lightweight coin or disk is arrested in transit through the chute and is caused to be ejected through a slot or opening 26 provided in the rear edge of the chute, it being guided toward said opening by reason of the inclined character of the pawl seat portion 24—whose inclination is directed downwardly toward said opening 26.

But designated coins, namely, coins of the value intended to effect the delivery of the article to be vended, will overbalance the weight 25, thereby tilting the seat portion 24 and providing the necessary clearance to permit passage of such coin through the chute for delivery to slot 8.

Also at the rear, upper portion of chute 13 I mount a magnet 27, capable of attracting magnetizable disks and drawing them out of the chute through opening 26. In Fig. 2 I have shown a disk, as B, in the act of being drawn through opening 26 by the magnet, and also a non-magnetizable disk, as C, of light weight, in the act of ejection from the balanced seat 24.

Also in Fig. 2 I have shown a designated coin A as lodged on seat 7, and a following coin or blank A' striking said lodged coin tangentially and thereby being ejected through opening 14.

For a washer or disk having a central hole, and which is of sufficient weight to pass the balanced arresting and ejecting device becoming engaged in slot 8 and lodged on seat 7, I provide other ejection means of the following character.

Lugs 28 carried by the plunger 1 serve as bearings for a rod 29, on which is carried a hook 30, whose point is inclined toward the slot 8 in position to impale an orificed coin or blank D lodged in said slot. A post 31 extends vertically from rod 29 and is urged rearwardly against a stop 32 by the tension of a spring 33 connecting said post with a rearward post 34 mounted on the plunger. Also the rod 29, at its ends, carries the rearwardly inclined legs 35 that are adapted to bear against lugs 36 projecting from the opposite sides of plate 5. The effect of spring 33 is superior to that of spring 12, and therefore, as the plunger is being drawn forwardly, causing the hook 30 to impale the coin or disk the legs 35 press against lugs 36 and depress plate 5, thereby releasing the coin or disk D from its seated engagement with slot 7, and permitting spring 12 to retract said plate 5 before lever 6 has been rocked a sufficient degree, (in the organism of my said earlier application, Serial No. 451,948) to permit spring 9 to effect an article ejection. In fact a stop 37, mounted on plunger 1, arrests the further rearward movement of post 31 at the point in the operation of legs 35 when they have spread the plate 5 apart from plunger 1 sufficiently to release the orificed coin or disk, because the impaling hook 30, in its concurrent upward movement, will have lifted the coin or disk (when the orifice thereof is small) to assist in effecting its dislodgment. Therefore the continued forward pull of plunger 1 will be idle movement, and in its return motion the coin or disk will strike against the end of plate 5 and thereby be shifted off

hook 30, falling therefrom into the coin box.

Obviously, when a designated coin is lodged in the seat 7 and slot 8 the hook 30 will merely bear against the surface of such coin as the plunger 1 is pulled outwardly, and consequently no co-action between the legs 35 and lugs 36 can occur to interfere with the article ejecting operation of the machine.

Variations within the spirit and scope of my invention are equally comprehended herein.

I claim:—

15 1. The combination, in a vending machine, of a coin chute having an edgewise outlet, said chute being inclined downwardly in the vertical plane of said outlet, and the edge surface of said chute whose plane intersects the vertical medial line through the chute provided with following inward and outward curvatures, coin lodgment means located beneath said chute with its centre at one side the vertical centre of said chute 20 exit, whereby a following coin or disk will strike a lodged coin tangentially and be discharged through said outlet.

20 2. The combination, in a vending machine, of means provided with a coin reception slot, a chute for the passage of coins, located in spaced relation beneath said slot, the centres of said slot and chute mouth being unaligned, the upper end of said chute having an edge opening under said slot, and 25 guide means to direct a coin from said slot, through said edge opening, into said chute.

30 3. The combination, in a vending machine, of means provided with a coin reception slot, a chute for the passage of coins located in

spaced relation beneath said slot, said chute 40 being edgewise inclined, the centres of said slot and chute mouth being unaligned, the upper end of said chute having an edge opening under said slot, and guide means to direct a coin from said slot through said 45 edge opening, into said chute.

4. The combination, in a vending machine having coin seating means whereby a coin may form an operative part of the machine, of means for impaling an orificed coin or disk lodged in said seating means, said means comprising a pendent hook curved to direct its point toward the coin or disk and means for concurrently releasing said seating means from said orificed coin or disk. 50 55

5. The combination, in a vending machine having a plunger with a coin slot therein, a guide for the plunger, a pivotal member with a coin seat beneath said plunger, and a spring to hold said member against said guide, of a hook to impale an orificed, seated coin or disk, hook carrying means pivoted to said plunger, tensional means to urge said hook toward its impaling action, tension restraining means operative in the normal position of said plunger, means carried by said hook carrying means to co-act with said pivotal member in the forward movement of said plunger, and release its coin seat from a lodged, orificed coin or disk, concurrently 60 65 with the impaling action of said hook, and a stop to limit the tensionally urged movement of said hook.

Signed at the borough of Manhattan, in the city, county, and State of New York, 75 this 8th day of April A. D., 1921.

CHARLES J. PAULSON.
